CLAIM

The ornamental design for a mobile communication device, as shown and described.

DESCRIPTION

FIG. 1 is a front perspective view of the mobile communication device.

FIG. 2 is a rear perspective view of the mobile communication device.

FIG. 3 is a front view of the mobile communication device with the detachable processor removed.

FIG. 4 is a front plan view of the mobile communication device.

FIG. 5 is a rear plan view of the mobile communication device.

FIG. 6 is a left side view of the mobile communication device.

FIG. 7 is a right side view of the mobile communication device.

FIG. 8 is a top view of the mobile communication device; and,

FIG. 9 is a bottom view of the mobile communication device.

The broken lines shown in the figures that are immediately adjacent to the shaded areas and define unshaded regions represent the bounds of the claim. All other broken lines, including the features within broken line boundaries and the broken lines on the front surface, the display rectangle, and the icons are directed to environment. The broken lines form no part of the claimed design.

1 Claim, 7 Drawing Sheets
